(57) **CLAIM**

The ornamental design for an insect trap, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a perspective view of an insect trap;

FIG. 2 is a front view of the insect trap;

FIG. 3 is a back view of the insect trap;

FIG. 4 is a right view of the insect trap;

FIG. 5 is a left view of the insect trap;

FIG. 6 is a top view of the insect trap; and,

FIG. 7 is a bottom view of the insect trap.

The left view is a mirror image of the right view.
